UNITED STATES PATENT OFFICE.

FERDINAND BUCHHOLTZ, OF JIM FALLS, WISCONSIN.

ADJUSTABLE CHIMNEY CLEANER.

Application filed June 30, 1926. Serial No. 119,709.

The invention relates to means for cleaning chimneys, flues and the like, through which smoke and products of combustion pass and which foul by free carbon depositing upon the walls thereof.

The invention provides a device which is adjustable to different sized flues or to flues of the same size to regulate the pressure exerted by the soot removing elements.

10 While the drawings illustrate a preferred embodiment of the invention it is to be understood that in adapting the means to meet specific needs and requirements, the design may be varied and such other changes in the 15 minor details of construction may be resorted to within the scope of the invention as claimed, without departing from the spirit thereof.

For a full understanding of the invention 20 and the merits thereof, reference is to be had to the following description and the drawings hereto attached, in which,—

Figure 1 is an elevational view partly in section, of a chimney cleaner embodying the 25 invention,

Figure 2 is a top plan view of the cleaner, partly in section,

Figure 3 is a fragmentary elevational view, and

30 Figure 4 is a detail perspective view of a wedge.

Corresponding and like parts are referred to in the following description and designated in the several views of the drawings 35 by like reference characters.

The device comprises a rod 1 having an eye 2 at one end and threaded throughout its length. A spider is mounted centrally upon the rod 1 and comprises a center piece 40 3 and cross heads 4 at the ends and sides of the center piece. Flat springs 5 are secured intermediate their ends to the cross heads of the spider and are provided at their ends with cleaning elements 6 which preferably 45 consist of brushes. A wedge 7 is interposed between the head of each of the brushes 6 and the spring 5 to give the proper set to the brush according to the adjustment of the device. The brushes 6 are readily detachable from the flat springs 5 and the wedges 50 7 are adapted to be replaced by other wedges 7^a, as indicated in Figure 4. The device is provided at opposite sides and at an intermediate or 3rd side, with a spring 5 and brushes 6 at opposite ends of the springs. 55

A spring 8 is located at the 4th side and its

end portions curve outwardly and inwardly, as indicated at 9, to ride upon a wall of the chimney. The spring 8, with its curved ends 9, constitutes a guide to travel upon a wall of a chimney. By giving the device a one quarter turn the fourth wall of the chimney may be cleaned. If the spring 8 and the diametrically opposite spring 5 be omitted two walls of the chimney only may 60 be cleaned at one operation, the other two walls being cleaned by a subsequent operation after the device has been given a one quarter turn as will be readily appreciated.

Spreaders 10 are threaded upon the rod 1 and are interposed between end portions of the springs 5 and adjustment of the spreaders along the rod 1 regulates the distance between the outer ends of the springs 5 and the brushes, or cleaning elements 6, carried thereby. Auxiliary spreaders 11 are adapted to be connected to the spreaders 10 to move therewith and engage end portions of the spring guide 8 and the diametrically opposite spring 5 to regulate the distance apart 70 of the curved ends 9 and the cleaning elements 6 which engage opposite walls of the chimney or flue.

The weight of the device is ordinarily sufficient to lower the same in a chimney or flue, but should it be necessary the device may be weighted to cause it to descend when lowered in a chimney, a cord, not shown, being attached to the eye 2 of the rod 1. A movement of the device upward and downward in the chimney effects a cleaning thereof by removing soot and other accumulation from the walls. The spring arms admit of the cleaners 6 adapting themselves to inequalities in the walls of the chimney or flue.

Having thus described the invention, I claim:

1. In combination a threaded rod, a spider mounted upon the rod intermediate its ends, flat springs attached to opposite sides of the spider, cleaning elements at the outer ends of the springs, intermediate flat springs attached to opposite sides of the spider, the one having its ends recurved and the other provided with cleaning elements, a spreader threaded upon the rod and engaging the first mentioned springs and an auxiliary spreader loose upon the rod and adjustable with the spreader threaded to the rod and adapted to adjust the said intermediate 80 springs.
2. A chimney cleaner comprising a thread-

ed rod, a spider on the rod, two flat springs secured intermediate their ends to opposite sides of the spider and having cleaning elements at their outer ends, intermediate flat 5 springs attached midway of their ends to opposite sides of the spider, one of said intermediate springs having opposite end portions recurved to ride upon a wall of the chimney and the other intermediate spring

having cleaning elements at its ends, spreaders threaded upon end portions of the rod and in contact with the first mentioned springs, and other spreaders loose upon the rod and movable with the spreaders threaded to the rod and in contact with the intermediate springs only. 10 15

In testimony whereof I affix my signature.
FERDINAND BUCHHOLTZ. [L.S.]
